UNITED STATES PATENT OFFICE.

GEORGE W. SPALDING, OF WORCESTER, MASSACHUSETTS, ASSIGNOR, BY MESNE ASSIGNMENTS, TO MILLS WOVEN CARTRIDGE BELT COMPANY, OF WORCESTER, MASSACHUSETTS, A CORPORATION OF MASSACHUSETTS.

WOVEN CARRIER.

1,338,794.

Specification of Letters Patent.

Patented May 4, 1920.

Application filed April 10, 1917. Serial No. 160,986.

To all whom it may concern:

Be it known that I, GEORGE W. SPALDING, a citizen of the United States, residing at Worcester, in the county of Worcester, 5 State of Massachusetts, have invented a certain new and useful Improvement in Woven Carriers, of which the following is a specification, reference being had therein to the accompanying drawings.

10 The invention has relation to pocketed carriers made of woven material, namely carriers on the order of those which are used for holding and carrying cartridges, packaged first-aid supplies, etc. The class 15 of pocketed carriers to which the invention is applicable includes cartridge-carriers, hospital corps belts, medical officers' belts, and others having special adaptations.

The invention comprises improvements in 20 the general construction of pocketed carriers. Also improvements in woven box-cover blanks.

The improvements in the general construction of pocketed carriers just mentioned consist, primarily, in a carrier comprising a body-web or band, a pocket thereon rising at its top above the top edge of the said body web or band, and a box-cover or hood flexibly attached to the body-web 30 or band and adapted to completely encircle or surround the upstanding top portion of the pocket without slits or openings around such portion.

The improvements in woven box-cover 35 blanks provide for the convenient production of box-covers or hoods.

The drawings illustrate an embodiment of the invention.

Figure 1 is a perspective view of a portion 40 of a carrier embodying the invention. The said figure shows a portion of the body-web or band and in connection therewith two pockets and their box-covers or hoods.

Fig. 2 is a perspective view of a cover-blank 45 with its wings opened out laterally and its narrow flanges or "widenings" upstanding.

Fig. 3 shows the said blank in substantially the folded condition in which it preferably is woven, after the floated portions 50 of the warp-threads have been cut away.

Fig. 4 is a view in section in the plane indicated by the dotted line 4, 4, of Fig. 3.

Fig. 5 is a perspective view of one pocket

of a carrier showing a second mode of carrying the invention into effect.

Fig. 6 is a perspective view of a blank such as is used in making a box-cover or hood like that shown in Fig. 5.

Fig. 7 is a view of the box-cover or hood of Fig. 5 in section in the plane indicated by line 7, 7, in the latter figure.

The body or band-portion 1 of the carrier shown in Fig. 1 and the pockets 2, 2, thereon, are composed of flexible woven material, 65 as already indicated herein. The carrier may be furnished with one pocket only, or with a plurality of pockets, according to the purpose which the carrier is designed to serve. In Fig. 1 the cover or hood of one 70 of the pockets is shown turned back so as to uncover such pocket, while that of the other pocket is closed down over the top of the latter. In practice the size and proportions of a pocket and of its cover may vary from 75 those indicated in the drawings.

Fig. 1 shows the feature of the upward extension of the top portion of a pocket above the top edge of the body or band-portion 1. It shows also the manner in 80 which the cover or hood of a pocket when in closed position, as at the right hand side in Fig. 1, fits over and around the upstanding top portion of the pocket. It further shows the connection of a cover or hood 85 with the body or band-portion by means of a flexible downward extension 3 of the back of the cover or hood. This extension may be applied and attached to the body or band-portion in various ways; it is shown in 90 the drawings as entered into a housing slit 4 formed for its reception in the upper margin of the body or band-portion, and as secured in such housing slit by means of 95 stitches 5 passing through the two thicknesses of the top margin of the body or band-portion and also through the extension 3 located between such thicknesses.

The cover or hood comprises a top 6, a back 7, a front 8, and opposite side-wings or 100 skirts 9, 9. These are all combined in such manner that when the cover or hood is closed down as at the right hand side in Fig. 1 it completely covers and encircles the upstanding top of the pocket, as is indicated 105 clearly in Fig. 1, without any slits or openings around such portion of the pocket.

The different portions of the cover or hood

are all integral parts of a one-piece blank, one form of which is shown in Fig. 2. The said blank comprises a rear extension 3^a, 7^a, an intermediate section 6^a having lateral widenings 9^a, 9^a, and a front extension 8^a. In making the box-cover or hood into shape and preparing it for attachment to the body or band-portion 1, the lateral widenings 9^a, 9^a, are bent down to produce the side-wings 10 or skirts 9, 9, of the box-cover or hood, the rear and front extensions are bent down to form the back 7 and front 8 thereof, and the side margins of the back and front are united to the rear and front marginal portions of the side-wings or skirts, as by 15 stitches 10, 10, thereby giving the cover or hood the required closed box-like shape adapted to fit over and completely encircle or surround the upstanding top of the 20 pocket. The box-cover or hood is then attached to the carrier by means of the extension 3 constituted by the part 3^a of the blank, and the stitches 5 or other fastenings 25 engaging with such extension and with the body or band-portion.

As stated at the outset herein, the portions of the back and front of the cover or hood which are united to the rear and front marginal portions of the side-wings or skirts 30 by means of the stitches 10, 10, namely the side margins of the back and front, are overlapped flatwise with the said marginal portions of the side-wings or skirts, one mode of overlapping being shown in Fig. 35 1. The said side margins are constituted by flanges 3^b, 3^b, and 8^b, 8^b, in the case of the blank that is shown in Fig. 2 and employed in making the box-cover or hood of Fig. 1. These flanges are formed with firm selvages, 40 bound and finished in the weaving. In the said figure, for convenience in illustrating the features of the blank, the flanges are shown standing at right angles to the plane of the main portions of the blank. When 45 the blank is bent into the shape of the box-cover or hood shown in Fig. 1, the flanges (turned at right angles as just referred to) are caused to lie flatly against the outer faces of the marginal portions 9^b, 9^b, 9^b, 9^b, of the side-wings or skirts 9^a, 9^a, as represented in Fig. 1, so that when stitches 10, 50 10, are formed the result will be the desired flat seams. As will be perceived, the raw or cut edges of the said marginal portions 55 9^b, 9^b, etc., of the side-wings or skirts are inclosed and concealed by the selvaged flanges of the front and back.

The one-piece blank shown in Fig. 2 may be woven conveniently in a comparatively 60 narrow loom by so disposing the warp-threads in such loom, and so conducting the weaving, as to produce the said blank in the folded state that is represented in Figs. 3 and 4. In these figures the flanges 3^b, 3^b, 65 8^b, 8^b, overlap the main portions 3^a, 7^a, and

8^a, and occupy a plane parallel with that of the said main portions, while the side-wings or skirts 9^a, 9^a, occupy planes parallel with that of the main portions, the said side-wings or skirts overlapping the top-section 70 6^a and each other. The production of the blank in the said folded state is effected readily by following well-known procedure in weaving. A connected series of blanks is produced in the form of a continuous 75 web, and is separated into individual blanks by cutting across such web intermediate successive pairs of the overlapping side-wings or skirts. Between one pair of side-wings or skirts and the next the warp-threads 80 employed in weaving the side-wings or skirts will be floated in an unwoven state, and will be trimmed away subsequent to the weaving so as to leave the blank free from free and loose ends of such warp-threads, 85 as in Figs. 2 and 3. Usually, at the places where the side-wings or skirts 9^a, 9^a, are formed, the warp-threads which are employed in the marginal flanges 3^b, 3^b, 8^b, 8^b, 90 will be floated in an unwoven state from the 90 ends of one of such pairs of flanges to the beginnings of the other of such pairs, and be trimmed off subsequent to the weaving. The result of weaving the said marginal flanges 3^b, 3^b, 8^b, 8^b, in a plane parallel with 95 that of the main portions of the blank, is that bends or folds are produced in the weaving along the lines on which said flanges are united with the main portion, creating fold-lines which render any subsequent bending or folding operation unnecessary and thereby facilitate the work 100 of making-up a cover or hood.

If desired, other methods may be followed in producing the blanks. Thus they 105 may be woven in an opened-out or transversely-extended flat state, if deemed advisable.

In some cases, as previously stated and as illustrated by Figs. 5 and 6, flat cut-edged 110 marginal portions at the rear and front of the side-wings or skirts may be turned inwardly at right-angles and interlapped with flat selvaged flanges of the back and front of the box-cover or hood, in such manner 115 that the cut edges of the said inturned marginal portions will be concealed by the said selvaged flanges. In Figs. 5 and 6 the rear extension 3^c, 7^c and front extension 8^c are formed in the weaving operation with split, 120 divided, or double selvages 3^d, 3^d, and 8^d, 8^d. When the blank is bent into shape for a box-cover or flap, the raw or cut edges 6^d, 6^d, of the side-wings or skirts 9^d, 9^d, are inserted between the respective pairs of selvaged margins comprising the said split divided, or double selvages, and are secured 125 by the stitches 10^d, 10^d. This method of construction, also, produces flat seams.

The body-web or band and pocket or pock- 130

ets may be woven integral with each other, by well-known processes of weaving, with or without the housing slit in the body-web or band. As one feature of the invention, 5 however, I produce the body-web or band, a woven pocket or pockets, and a cover or covers of woven material, all made separately as separate articles, and combine and fasten them together in the process of manufacture, by attaching the pocket or pockets to the body-web or band, and properly attaching the cover or covers.

My invention produces a square box-cover or hood, namely one having the sides there- 15 of at right-angles with the top, back, and front.

As usual, fastening devices are provided for holding the cover or hood securely closed when required, as at the right in Fig. 1. 20 The drawings show means of ordinary character, comprising a stud 11, applied to and projecting from the front wall of the pocket, and a coöperating socket 12 applied to the front of the cover or hood.

25 What is claimed as the invention is:—

1. A woven carrier comprising a body- web or band, a pocket fixedly attached thereto rising at its top above the top edge of

the said body-web or band, and a box-cover or hood for said pocket flexibly attached 30 to the body-web or band, and which completely encircles or surrounds the upstanding top-portion of the pocket without slits or openings around such portion.

2. A one-piece box-cover blank comprising 35 a rear extension adapted to constitute an attaching portion and a box-cover back, an intermediate top-section having lateral widenings adapted to constitute side-wings or skirts, and a front extension adapted to 40 constitute the front of the cover, said rear and front extensions having selvaged side marginal flanges adapted to overlap flat- wise with the marginal portions of the side- wings or skirts and the said blank having 45 as produced in the weaving bends or folds along the lines on which the said flanges are united with the main portion, creating fold-lines.

In testimony whereof I affix my signa- 50 ture in presence of two witnesses.

GEORGE W. SPALDING.
